UNITED STATES PATENT OFFICE.

RAY C. SIMPSON, OF DALLAS, TEXAS.

WATER-COCK FOR WATER-HEATERS.

No. 854,588.

Specification of Letters Patent

Patented May 21, 1907.

Application filed October 5, 1906. Serial No. 337,587.

To all whom it may concern:

Be it known that I, RAY C. SIMPSON, a citizen of the United States of America, residing at Dallas, in the county of Dallas and State 5 of Texas, have invented certain new and useful Improvements in Water-Cocks for Water-Heaters, of which the following is such a full, clear, and exact description as will enable others skilled in the art to which it appertains to make and use the same.

This invention has for its primary object the provision of means whereby a water-heater will be automatically drained of water when the water supply is cut off at the 15 main or house supply pipe and with this object in view, and such other incidental objects as will hereinafter appear, the invention consists in certain novel features of the device illustrated in the accompanying 20 drawings as will be hereinafter first fully described and then particularly pointed out in the claims.

In the drawings, Figure 1 is a front elevation of a water heater having my present invention applied thereto, Fig. 2 is a vertical section of my improved water cock; Fig. 3 is a detail view of the plunger or valve showing the position when the cock is closed and the main water supply pipe is open; Fig. 4 30 is a similar view showing the position of the valve when the water supply is cut off; Fig. 5 is a similar view showing the position of the parts when the valve is held open, and Fig. 6 is a detail plan view of the plunger 35 guide.

The water heater, 1, preferably rests on a shelf, 2, supported by brackets, 3, but it may, of course, be arranged on any convenient support. Water is supplied to the 40 heater through a cock, 4, and circulates in the heater so as to be acted upon by the flame and heat from a gas-burner therein which is supplied through a gas-cock, 5, the stems of the valves in the gas and water 45 cocks being coupled together, as shown at 6, so that neither cock can be opened or closed without simultaneously opening or closing the other cock. The construction of the heater and the gas-cock, however, form no 50 part of my present invention and further detailed reference thereto is not necessary herein.

The casing, 7, of the water-cock is disposed vertically on the heater and its lower 55 end communicates with the water main or house supply pipe. The stem, 8, enters the

casing through the side of the same and extends horizontally across the same, being mounted to rotate in a stuffing box, 9, on one side of the casing and in a bearing or circular seat, 10, formed on the opposite wall. The stem is formed with a crank or eccentric portion, 11, near its end, which passes transversely through a slot, 12, in the plunger or valve. This plunger or valve consists of an 60 upper flat plate-like portion, 13, containing the slot 12, a substantially cylindrical portion, 14, depending from the lower end of the upper flat portion, and a horizontally disposed head or disk portion, 15, at the lower end of 65 said cylindrical portion. The cylindrical portion of the valve fits closely in and plays through a horizontal partition or seat, 16, in the casing and is provided with suitable openings or grooves, 17, in its sides for the 70 passage of the water. The horizontal disk or head 15 projects beyond the cylindrical body 14 and is arranged to fit closely against the under side of the partition 16 and cut off 75 the flow through the same. The flat portion, 80 13, of the valve plays in notches or guideways, 18, in an annular shoulder or flange, 19, in the upper portion of the casing, the concave edges of the shoulder between 85 said notches presenting open spaces through which the water may flow on its way into the heater.

The slot 12 in the valve, it will be noticed, has two branches, 20, 21, forming a right angle, the vertical branch 20 being near one 90 edge of the plate and parallel therewith.

When the cocks are closed and the water turned on at the house supply pipe, the valve will assume the position shown in Fig. 3, in which the crank 11 is disposed vertically and 95 registers with the vertical branch of the slot. The pressure of the water, in this position of the valve, carries the disk 15 against the seat or partition 16 and holds it firmly against the same so that the flow of water into the heater 100 is prevented. Should it be desired to admit water into the heater the stem is turned forward and downward thereby causing the crank 11 to ride upon the lower wall of the horizontal branch of the slot and depress the 105 valve as clearly shown in Fig. 5, the engagement of the crank and the slot holding the valve open, as will be readily understood. When the valve is thus lowered, the water 110 will flow over the edge of the disk and through the grooves 17 into the space above the partition 16 whence it will pass into the heater.

When the flow of water into the heater is to be cut off, the stem is rotated in the reverse direction and will lift the valve back to the seat to the position shown in Fig. 3. If, now, 5 the water should be cut off at the main or house supply pipe, the valve will at once drop, owing to the removal of the water pressure, and will uncover the opening in the valve seat so that all the water in the heater 10 will flow backward through the valve casing and around the valve into the water main and the heater will be automatically drained. In this position of the valve, as shown in Fig. 15 4, the vertical branch of the slot engages over the crank of the valve stem and prevents rotation of the same as any attempt to rotate it will simply cause the valve to bind against the side walls of its seat without producing any lifting of the same. Consequently, 20 the valve can not again be manipulated until the water is admitted through the house supply pipe and its pressure carries the disk against the seat and brings the horizontal branch of the slot into registry with the 25 crank. Inasmuch as the gas cock is coupled to the water cock, the heater can not be used when the house or main water supply is cut off.

Having thus described my invention, what 30 I claim and desire to secure by Letters-Patent is:—

1. The combination of the water cock casing, a valve therein having a slot provided with vertical and horizontal branches and 35 having a disk or head at its lower end arranged to bear against the under side of its seat, and an operating stem rotatably mounted in the casing and having an eccentric portion playing in the branched slot in 40 the valve the length of the slot exceeding the

thickness of the eccentric portion within the slot whereby when the eccentric portion is disposed longitudinally of the casing the valve may move from its seat automatically upon a reduction of the fluid pressure. 45

2. The combination of the water cock casing, a valve seat therein, a guideway in the casing above the valve seat, a valve having an upper portion playing in the guideway and provided with a branched slot, and a 50 disk at its lower end arranged to bear against the under side of the valve seat, and an operating stem having a crank engaging the branched slot the length of the branches of the slot being greater than the thickness of 55 that portion of the crank which passes through the same whereby when the crank is disposed longitudinally of the casing a free movement of the valve will be permitted.

3. The combination of the water cock casing, a valve seat therein, a valve comprising a cylindrical body playing through said seat and having grooves in its sides, a disk-like head on the lower end of said body arranged to bear against the under side of the valve 65 seat, and a plate-like portion rising from the upper end of said body and provided with a right-angled slot having vertical and horizontal branches, and a rotatable stem mounted transversely in the casing and having a 70 crank engaging said slot, the said crank being in registry with the vertical branch of the slot when the valve is closed.

In testimony whereof, I have signed this specification in the presence of two subscribing witnesses.

RAY C. SIMPSON.
